SNOW SLED

Raymond G. Lankowitz, 4700 W. 32nd Ave.,
Denver, Colo. 80212

Filed Jan. 10, 1969, Ser. No. 15,311

Term of patent 14 years

Int. Cl. D21—03

U.S. Cl. D34—15

FIG. 1

FIG. 2

FIG. 3

FIG. 4

FIG. 5

FIG. 6

FIG. 1 is a top plan view of the snow sled showing my new design;

FIG. 2 is a bottom plan view thereof;

FIG. 3 is a sectional view taken about lines 3—3 of FIG. 1;

FIG. 4 is a front elevational view thereof;

FIG. 5 is a rear elevational view thereof; and

FIG. 6 is a side elevational view thereof.

The characteristic feature of this invention is the rounded shell-like body having a squared, rearward end configuration.

I claim:

The ornamental design for a snow sled, as shown.
